[57] **CLAIM**

The ornamental design for a bullet collator for shell reloading operations, as shown.

DESCRIPTION

FIG. 1 is a perspective view of a bullet collator for shell reloading operations showing my new design;

FIG. 2 is a perspective view of a bullet collator ring and rejecter plate illustrated within FIG. 1;

FIG. 3 is a top plan view of a rejector plate illustrated within FIGS. 1 and 2;

FIG. 4 is an end elevational view of a rejector plate illustrated within FIGS. 1 and 2;

FIG. 5 is an opposite end elevational view of a rejector plate illustrated in FIGS. 1 and 2;

FIG. 6 is a top plan view of a bullet collator for shell reloading operations; and,

FIG. 7 is a side elevational view of the bullet collator of FIG. 1.

FIG. 1

FIG. 2

FIG. 3

FIG. 5

FIG. 4

FIG. 6
